[57] CLAIM

The ornamental design for a clock, as shown and described.

DESCRIPTION

FIG. 1 is a front perspective view of a clock showing my
new design;

FIG. 2 is a rear perspective view of a clock thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line showing of a support structure is for
illustrative purposes only and forms no part of the claimed
design.
